UNITED STATES PATENT OFFICE.

JOHN B. FAIR, OF GREEN TOWNSHIP, ST. JOSEPH COUNTY, INDIANA.

SILO.

1,162,995.

Specification of Letters Patent.

Patented Dec. 7, 1915.

Application filed June 17, 1914. Serial No. 845,510.

To all whom it may concern:

Be it known that I, JOHN B. FAIR, a citizen of the United States, residing in Green township, in the county of St. Joseph and State of Indiana, have invented certain new and useful Improvements in Silos, of which the following is a specification.

This invention relates generally to an improvement in silos and particularly to a joint formation between the meeting ends of the silo stave sections, whereby said ends are actively connected in a fluid-tight manner and held against independent separation in any direction from pressure from within.

The main object of the present invention is the provision of a stave designed primarily for silo construction and made up of a series of sections each formed at the respective ends with a particular and specific joint construction, to insure an interfitting and interlocking of the meeting ends of the sections to obviate possibility of independent movement when the sections are in silo-forming relation.

The invention in the preferred form of details will be described in the following specification, reference being had particularly to the accompanying drawings, in which:

Figure 1 is an elevation of a silo utilizing the improved staves in its construction. Fig. 2 is an enlarged elevation illustrating a single row of vertically-disposed sections in connected relation. Fig. 3 represents opposing edge views of a single stave section. Fig. 4 is an end view of one of the stave sections. Fig. 5 is a section on line 5—5 of Fig. 1.

The salient feature of the present invention resides in the formation of the ends of the particular stave sections, it being understood that the thickness or character of the material utilized, as well as the size characteristics of the stave section are unimportant so far as the present invention is concerned, and that any and all variations in these particulars are contemplated.

The stave section forming the subject matter of this invention is formed at the respective ends to present edge off-sets or projections 1 and 2, each preferably including one-half the width of the stave section. The projections are of substantial extent longitudinally of the stave section, and are opposingly located, the projection 1, shown at the upper end of the stave section extend-

ing coincident with one side edge of the stave section, as 3, while the projection 2, shown at the lower end of the stave section, is coincident with the opposing side edge, as 4. As thus arranged in outline form the stave has its side edges 3 and 4 approximately parallel, and the end edges presenting an outline projecting at right angles to the side edge 3, as at 5, and extended for half the width of the stave section, then projected vertically of the stave section as at 6, preferably in coincidence with the longitudinal median line of the stave section, and projected at right angles as at 7, to the remaining side edge 4.

In the further formation of the stave section one-half the marginal edge outline thereof is formed with a tongue projection 8, and the opposing half with a groove formation 9, corresponding in size and shape to the tongue. In the instance shown the edge portions 3, 5, 6 and 7 are formed with the tongue 8, while the side edge 4 and the remaining end edges 5, 6 and 7 are formed with the groove. As clearly apparent from Fig. 3 the tongue is formed on the side edge 3 and the lower end edge, while the groove is formed on the side edge 4 and the upper end edge.

The stave sections are assembled in silo-forming relation, it being understood that the respective stave sections have the desired form in transverse section necessary to provide a silo of the desired sectional form in assembling the stave sections. It is to be understood that the sections herein referred to constitute independent molded elements and that assembled in endwise relation to form a row that constitute in such formation a stave.

The ends of a particular row of stave sections interfit, the tongues of the lower end edge fitting in the grooves of the upper end edge of the immediately underlying stave section, the shoulder projections 2 of the lower end edge of the stave section fitting against the shoulder projections 1 of the upper end of the next lowermost stave section. The side edges of the stave sections of any row interfit with the side edges of the stave sections of the adjacent row through the tongue and groove connection. I also prefer to utilize tie bands 10 encircling the silo wall and having meeting ends 11 to be drawn together by a bolt connection 12. The bands are preferably of a width to com-

pletely cover the end joint connections between the stave sections, as clearly apparent from Fig. 1. As thus constructed there is a complete matching of section ends at 5 their joint connection, the shouldered formation resisting lateral movement and the tongue and groove connection resisting surface pressure. The interlock will thus insure an absolutely tight formation of the 10 joint connections, it being obvious that from the duplicate end and side formation a particular single position of the section is not necessary, any or all of the sections being reversible.

15 What is claimed is:

A stave for silo construction made up of a plurality of duplicate sections arranged in endwise relation, each section being of approximately uniform width and thickness 20 and having the ends thereof presenting pro-

jections oppositely disposed with respect to the longitudinal median line of the section to present abrupt shoulders longitudinally of the section, the respective sections being arranged in opposing relation with respect 25 to their projections to provide an interfit locking edge section against independent lateral movement with respect to the endwise adjacent sections, each section being formed throughout its edge outline for interlocking fit with endwise adjacent sections and with lateral adjacent sections of the immediately adjacent staves.

In testimony whereof I affix my signature in presence of two witnesses.

JOHN B. FAIR.
